R. TATTU,
CORNER FOR BEDSTEADS,
APPLICATION FILED MAY 6, 1919.

1,337,627.

Patented Apr. 20, 1920.

Inventor

R. Tattu
By his Attorney
Frank Smith.

UNITED STATES PATENT OFFICE.

RADU TATTU, OF BROOKLYN, NEW YORK.

CORNER FOR BEDSTEADS.

1,237,627.

Specification of Letters Patent. Patented Apr. 20, 1920.

Application filed May 6, 1919. Serial No. 265,209.

To all whom it may concern:

Be it known that I, RADU TATTU, a citizen of the United States, and a resident of borough of Brooklyn, city of New York, in the county of Kings and State of New York, have invented a certain new and useful ⁵ Corner for Bedsteads, of which the following is a specification.

My invention relates to improvements in ¹⁰ corners for bedsteads and the like and the object of my invention is to provide a novel, simple and convenient device for the purpose specified.

I accomplish this object by the device ¹⁵ illustrated in the accompanying drawings, in which—

Figure 1 is a plan view of the device, partly in section,

Fig. 2 is a section of the same on the line ²⁰ 2—2 in Fig. 1 and

Fig. 3 is a view of an optional form of the device.

Similar characters refer to similar parts throughout the several views.

My improved corner comprises an anchor ²⁵ member 1 for a side bar and which is preferably secured upon the bed post 2 by means of bolts 3 or the like.

I prefer to construct the anchor member 1 ³⁰ in the form of a T having two branches or leaves 4 and 5.

The branch or leaf 4 extends forwardly and carries on its inner face a cam plate 6 which is preferably welded thereon and ³⁵ forms a seat for the tapered engaging tooth or plate 7 carried by the vertical flange of a side bar 8 of a bedstead. The bracket for the end bar of the bedstead comprises a U shaped member 9 upon the forward leg 10 of which member the end bar is adapted to be bolted or otherwise secured and the rear leg 11 is secured to the bed post 2 by means of the bolts 3 or in other like manner. I prefer to bend over an end section 12 of ⁴⁰ the leg 11 against the side of the bed post 2.

A bolt 13 may be inserted through the end section 12, post 2 and the leaf 5 to more securely attach the device to the bed post 2.

It will thus be apparent that the anchor ⁵⁰ member 1, which forms a bracket for the support of the side bar of the bedstead, and the bracket for the support of the end bar are adapted to be permanently and firmly secured to the bed post 2 and that the side ⁵⁵ bar 8 may be readily attached by inserting

it and its tapered engaging tooth 7 in the seat formed by the leaf 4, the cam plate 6 carried thereby and the U shaped bracket member 9 and that the side bar 8 may be readily lifted and raised out of its seat and ⁶⁰ removed or replaced when desired. The optional form of the device illustrated in Fig. 3 is more particularly adapted to be used with a round or cylindrical bed post 14 and is seated on a suitably shaped pillow 15 ⁶⁵ which is carried on the post 14. The support for the side bar 16 of the bedstead comprises an angle iron having two leaves, one of which leaves 17 rests against the pillow 15 and the other or forward leaf 18 carries ⁷⁰ on its inner face a cam plate 19 which forms a seat for the tooth 20 carried by the side bar 16 of a bedstead.

In this form of the device, the rearwardly extended leaf of the end bar bracket may ⁷⁵ be eliminated and the end bar supporting bracket comprises a U shaped member 21 having its rear leg 22 bound to the bed post 14 by means of a bolt or the like 23 which is passed through the leg 22, leaf 17, pillow ⁸⁰ 15 and bed post 14 and is retained by means of a nut 24 or the like. The forward leg 25 of the U shaped member 21 is adapted to be bolted to the end bar of a bedstead which is supported thereby. ⁸⁵

Having thus described my invention, what I claim is:

1. In a device of the character described, the combination of an anchor member comprising three leaves, two of said leaves being adapted to embrace a bedpost and the other of said leaves being provided with a cam block having an inclined edge to wedge a bar of a bedstead, and a bracket member secured to the anchor member and comprising four leaves, one of said leaves being secured to the bed post, one of said leaves lying against the anchor member, one of said leaves being positioned parallel with the cam block and spaced therefrom to form ⁹⁰ 100 a pocket for a vertical flange of a bar of a bedstead, and one of said leaves forming a support for a bar of the bedstead, and a bolt inserted in the bedpost and locking thereto a leaf of the anchor member and a ⁹⁵ leaf of the bracket member on opposite sides of the bed post.

2. In a device of the character described, the combination of an anchor member having a plurality of leaves, one of said leaves ¹⁰⁵ ¹¹⁰

being adapted to be secured to a bedpost and another of said leaves being provided with a cam block having an inclined edge to wedge a bar of a bedstead, and a bracket member having a plurality of leaves, one of said leaves of the bracket member being secured to the anchor member, one of said leaves of the bracket member being secured to the bed post, one of said leaves of the bracket member being spaced from the cam block of the anchor member to form a seat for the vertical flange of a side bar and one of the said leaves of the bracket member forming a support for an end bar of a bedstead.

3. In a device of the character described, the combination of an integral T-shaped anchor member, a branch thereof extending forwardly and carrying a cam block on its inner face to form a wedge for a tooth carried by the vertical flange of a side bar of a bedstead, a bracket for an end bar of a bedstead secured to the said anchor member and comprising a U-shaped member spaced from the said branch of the anchor

member to form a seat for said vertical flange of the side bar.

4. In a device of the character described, the combination of an integral T-shaped anchor member, a cam plate on a branch thereof and adapted to wedge a side bar of a bedstead, a bracket member secured to the anchor member and adapted to support an end bar of a bedstead and having an end section bent over against the bed post and secured thereto.

5. In a device of the character described, the combination of a T-shaped anchor member and a U-shaped bracket member spaced to receive between them the vertical flange of a side bar of a bedstead, blocks on the said anchor member and the said flange of the side bar and having inclined edges to wedge the side bar and means upon the bracket member to support an end bar.

Signed at New York, in the county of New York, and State of New York this 1st day of May, A. D. 1919.

RADU TATTU.
